UNITED STATES PATENT OFFICE.

JOSEPH J. WALSER, OF CHICAGO, ILLINOIS, ASSIGNOR TO THE GOSS PRINTING PRESS COMPANY, OF CHICAGO, ILLINOIS, A CORPORATION OF ILLINOIS.

PRINTING-PRESS.

1,073,450.

Specification of Letters Patent. Patented Sept. 16, 1913.

Application filed February 10, 1912. Serial No. 676,702.

To all whom it may concern:

Be it known that I, JOSEPH J. WALSER, a citizen of the United States, residing at Chicago, in the county of Cook and State of Illinois, have invented certain new and useful Improvements in Printing-Presses, of which the following is a specification, reference being had to the accompanying drawings.

10 My invention relates to printing presses, and its object is to provide a new and improved printing press mechanism, one of the principal objects of which is to provide a printing press whose printing cylinders are 15 of a length adapted to print a web of paper, of a width of one page length, and whose form cylinders contain one stereotype plate on each semi-circumference with the column rules running parallel with the axis of the 20 cylinder and in which a fourteen-page paper may be printed from a machine adapted to carry sixteen plates, a ten-page paper from a machine adapted to carry twelve plates, and a six-page paper from a machine adapted 25 to carry eight plates, and so on.

Another object of my invention is to provide a new and improved arrangement of the several sets of printing mechanism and printing couples in which the rolls of paper 30 are easily accessible, and the printing mechanisms so arranged that additional sets of printing couples may be readily added thereto.

In the drawings,—Figure 1 is a diagrammatic side elevation of a press containing my invention; Fig. 2 is a side elevation showing the driving gearing which I prefer to use; and Fig. 3 is a section on line 3—3 of Fig. 1.

Referring to the drawings,—in the form 40 in which I have illustrated my invention,—the press is provided with four sets of printing couples adapted to print from four rolls.

4 indicates the press frames and 5 the folding frame, which are preferably mounted 45 upon a single base, as 6.

As shown in the drawings, the press embodies four sets of printing mechanisms, A, B, C, and D, although the number, of course, may be more or less. Each of these presses 50 is composed of a set of printing couples comprising two form and two impression cylinders and corresponding inking mechanism. The four presses are arranged one behind the other in the same vertical plane, and the two printing couples of each press are arranged 55 above each other in the same vertical plane.

Referring to press A, 7 indicates the first form-cylinder and 8 a corresponding impression-cylinder. 9 indicates an inking mechanism for form-cylinder 7 of any well-known 60 form and description. 10 indicates the form-cylinder and 11 the impression-cylinder of the second printing couple, and 12 the inking mechanism for form-cylinder 10, which may be of any well-known and ap- 65 proved form and description. Press A normally is adapted to print from roll A'. The roll A' is of a width corresponding with a page length of the paper and the form cylinders 7 and 10 are of a corresponding length 70 and are each adapted to hold upon each semi-circumference a stereotype plate whose column rules run parallel with the axis of the cylinder. The web of paper, passing from web A', passes from form and impres- 75 sion cylinders 7 and 8, where it is printed upon one side, thence around guiding roll 13, between form and impression cylinders 10 and 11, thence around guiding rolls 14, 15, 16, between gathering rollers 17 and 18. 80

Referring to press B, the arrangement is precisely similar to press A and is adapted to normally print from a roll of paper B'. In press B 19 indicates the first form-cylinder, 20 the first impression-cylinder, 21 inking mechanism for form-cylinder 19, 22 the second form-cylinder, 23 its coating impression-cylinder, and 24 the inking mechanism, which may be of any well-known form and description. The web B', in one way of op- 90 erating the press, passes first between form and impression cylinders 19 and 20, thence over guide-roller 25, between form and im- 95 pression cylinders 22—23, thence over guide-rollers 26, 27, 28, to gathering rollers 17 and 18, where it is associated with web A'.

Press C is like the other presses in arrangement and is adapted to print from web C'. 29 indicates the first form-cylinder, 30 the first impression-cylinder, 31 inking 100 mechanism for the first form-cylinder, 32 the second form-cylinder, 33 the second im- pression-cylinder, and 34 inking mechanism for form-cylinder 32. The web C' passes over guide-roller 35, between form and im- 105 pression cylinders 29—30, thence around guide-rollers 36—37, between form and im- pression cylinders 32—33, where it is printed

upon the other side, thence over suitable guide-rollers, as 38, 39, 40, to the gathering rollers 17—18, where it is associated with the other webs.

- 5 Press D, which is like the other presses above described, is adapted to print from a web of paper D'. 41 indicates the first form-cylinder, 42 the first impression-cylinder, 43 inking mechanism for form-cylinder 41, 44 the second form-cylinder, 45 the second impression-cylinder, 46 inking mechanism for the second form-cylinder 44. The web D' passes around a suitable guide-roller, as 47, between form and impression cylinders 41—42, thence over suitable guide-rollers, as 48—49, between form and impression cylinders 44—45, thence around suitable guide-rollers, as 50—51, to the gathering rollers 17—18, where it is associated with the other webs. As thus used, the press, it will be seen, contains sixteen plates and is adapted to print a sixteen-page paper. The four webs gathered by the gathering rollers 17—18 and superposed in register with each other, are led between cylinders 52—53. The cylinder 52 is of a circumference equal to two page widths plus margins and is provided with a suitable cutting-blade 52^a which, coacting with corresponding cutting blocks 54—55 on cylinder 53, operates to sever the superposed webs upon every second transverse margin. The cylinder 53, which is of a circumference equal to four page widths, is provided with the usual folding-blades 56 which, operated in any well-known and approved manner, are adapted to engage the central margins of the sheets and tuck them between the usual folding rollers 57, which operate in the well-known way to fold the sheets transversely of their central margins, from which they may be delivered to any suitable folding and delivery mechanism, as 58, which is only conventionally illustrated, as it forms no part of my present invention. As thus run, the press will produce a sixteen-page paper consisting of four sheets, each containing four pages folded centrally on their central transverse margins.
- 59 indicates an impression-cylinder, 60 a coacting form-cylinder, and 61 suitable inking mechanism for form-cylinder 60 which is used in case it is desired to print one of the webs in a plurality of colors. In such case the web A' may not be used and the web B' is used. In this case the web B', after being led between form-cylinder 19 and impression-cylinder 20, is led, as indicated in dotted lines, around guide-roller 25^a and thence across around roller 13 between form cylinders 7 and 8, as indicated in dotted lines therein, thence between impression-cylinders 59 and 60, thence down over roller 13, between form-cylinder 10 and impression-cylinder 11, thence upward, as

indicated in dotted lines, over a suitable roller 62 and over roller 25, as indicated by dotted lines and arrows, down between form-cylinder 22 and impression-cylinder 23, and thence over rollers 26, 27 and 28, to the gathering rollers 17—18. In this case, of course, the form and impression cylinders 7—8 will have the direction of their rotation reversed, and this is done by any suitable and well-known mechanism.

In Fig. 2 I have shown the gearing for the press, which it is unnecessary to describe in full further than to say that 65—66 indicate the main driving pinions, which, by a suitable gearing (not shown), are connected up with the various moving parts of the press. For the purpose of reversing, a gear 67, which is a double-faced gear, is provided, and a gear 68, which is adapted to slide longitudinally upon its shaft so that by such sliding it may be brought into mesh with gear 67 for the purpose of reversing the same. This, however, I have shown only for purposes of illustration, as it is one well-known method of reversing the rotation of printing cylinders and of itself forms no portion of my present invention. By this means web B' may be printed on both sides only in black and upon one side with a plurality of colors, and this side, as is the obvious arrangement, will be the outside of the paper when it is folded.

For the purpose of producing a paper which may consist of six, ten, or fourteen pages, press C is provided with gearing by which it may be slowed down and driven at one-half the speed of the other presses. This may be done in any well-known and approved manner, as by gears 69—70 which are adapted to mesh, respectively, with gears 71—72, as is shown in Fig. 2. When the press is to be driven at full speed, the gear 69 is in mesh with gear 71. When slowed down to half speed, the gear 70 is brought into mesh with gear 72, which, in this case, does the driving of press C. As this slowdown mechanism may be of any well-known and approved form and construction, I have illustrated it only diagrammatically and only briefly referred to it in my description, as of itself it forms no part of my present invention. In this case, web C', being led through press C, which is driven at one-half speed, is printed upon both sides, and the forms upon each half of each form-cylinder will be duplicates of each other so that a series of two-page duplicate prints are produced by press C. The web thus printed, after being led around rollers 38—39, instead of being led over roller 40 to the gathering cylinders 17 and 18, is led between two cutting cylinders 73—74, which are of the well-known form and description, and are of one-half the diameter of the cutting cylinder 52 and are, therefore, adapted to sever

the web C' upon every transverse margin. These cutting cylinders are located the distance of a sheet width from gathering cylinders 17 and 18 and the sheets from web 5 C', therefore, after being severed into single two-page sheets, are led between the gathering cylinders 17 and 18, between the other webs in registry therewith, and the two-page product with the other four-page products 10 are folded out together between folding rollers 57-58. By thus using webs A', B', C', and D' with the press C slowed down to one-half of the speed, it is obvious that with a sixteen-plate machine a fourteen-page paper 15 can be produced. By silencing one or more of the printing presses, it will also be obvious that a ten-page paper will be produced on a twelve-plate machine, or a six-page paper upon an eight-plate machine, and so 20 on. By adding to the number of presses, corresponding changes, of course, may be made.

It will be understood that I do not restrict my invention to use in the precise 25 method of operation set forth above, except as specifically claimed, but that my devices may be operated in any appropriate manner without departing from my invention and the claims are to be construed accordingly.

30 What I claim as my invention, and desire to secure by Letters Patent, is—
 1. A printing press having, in combination, a plurality of printing mechanisms arranged one behind the other; each printing 35 mechanism being composed of two pairs of printing couples arranged one pair above the other and adapted to print upon a web one page length in width, the form-cylinders being adapted to contain upon each 40 semi-circumference a page form with the column rules running parallel with the axis of the cylinder, means for assembling the printed webs in registry, means for cutting said webs upon every other transverse margin, means for folding the severed sheets 45 transversely along their central margins, means for slowing down one of said presses to run at one-half speed, cutting mechanism adapted to sever said slowed-down web upon every transverse margin, means for leading the slowed-down web to said cutting mechanism, means for associating said severed sheets in registry with the other webs, and an auxiliary printing couple between which 50 one web may be led for printing in color in addition to the printing in black.

55 2. A printing press having, in combination, a plurality of printing mechanisms ar-

ranged one behind the other in the same vertical plane, each printing mechanism being composed of two pair of printing couples arranged one pair above the other and adapted to print upon a web one page length in width, the form-cylinders being adapted to contain upon each semi-circumference a 60 page form with the column rules running parallel with the axis of the cylinder, means for assembling the printed webs in registry, means for cutting said webs upon every other transverse margin, means for folding the severed sheets transversely along their central margins, means for slowing down one of said presses to run at one-half speed, cutting mechanism adapted to sever said slowed-down web upon every transverse margin, means for leading the slowed-down web to said cutting mechanism, means for bringing the severed sheets into registry with the other webs, and associating them therewith, and means adapted to lead one of 70 said webs through two of said sets of printing couples for the purpose of printing a plurality of colors thereon.

3. A printing press having in combination a plurality of printing mechanisms arranged one behind the other in the same vertical plane, each printing mechanism being composed of two pairs of printing couples arranged one pair above the other and adapted to print upon a web one page length 85 in width, the form-cylinders being adapted to contain upon each semi-circumference a page form with the column rules running parallel with the axis of the cylinder, cutting mechanism adapted to cut a web upon 90 every transverse margin, a second cutting mechanism adapted to cut a web upon every alternate transverse margin, to either of which cutting mechanisms one of said webs may be directed, means for driving at either 100 half-speed or full-speed the printing mechanism by which said last-named web is produced and for driving the other printing mechanisms at full speed, means for reversing the direction of driving of certain of 105 said printing couples whereby a web may be led through two of said printing mechanisms for printing thereon in a plurality of colors, means for associating said severed sheets in registry, and means for folding 110 said sheets together to make a complete paper.

JOSEPH J. WALSER.
